US00D875725S

(12) **United States Design Patent** (10) **Patent No.:** **US D875,725 S**
Hintermann et al. (45) **Date of Patent:** **** Feb. 18, 2020**

(54) **COVER FOR ELECTRONIC COMMUNICATIONS DEVICE**

(71) Applicant: **HTC CORPORATION**, Taoyuan (TW)

(72) Inventors: **Mathias Andreas Hintermann**, San Francisco, CA (US); **Stuart Kyle**, San Francisco, CA (US)

(73) Assignee: **HTC Corporation**, Taoyuan (TW)

(**) Term: **15 Years**

(21) Appl. No.: **29/559,987**

(22) Filed: **Apr. 1, 2016**

(51) LOC (12) Cl. **14-03**

(52) U.S. Cl.

USPC **D14/250**

(57) **CLAIM**

The ornamental design for a cover for electronic communications device, as shown and described.

DESCRIPTION

FIG. 1 is a front perspective view of a first embodiment of a cover for electronic communications device in accordance with our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view of the cover for electronic communications device when opened;

FIG. 9 is a front perspective view of a second embodiment of a cover for electronic communications device in accordance with our new design;

FIG. 10 is a front view thereof;

FIG. 11 is a rear view thereof;

FIG. 12 is a left side view thereof;

FIG. 13 is a right side view thereof;

FIG. 14 is a top plan view thereof;

FIG. 15 is a bottom plan view thereof;

FIG. 16 is a front perspective view of the cover for electronic communications device when opened;

FIG. 17 is a front perspective view of a third embodiment of a cover for electronic communications device in accordance with our new design;

FIG. 18 is a front view thereof;

FIG. 19 is a rear view thereof;

FIG. 20 is a left side view thereof;

FIG. 21 is a right side view thereof;

FIG. 22 is a top plan view thereof;

FIG. 23 is a bottom plan view thereof; and,

FIG. 24 is a front perspective view of the cover for electronic communications device when opened.
